United States Patent Office

Des. 179,898
Patented Mar. 19, 1957

179,898

PLASTIC BASKET

Nathaniel Hyman, Hewlett, N. Y., assignor to Jaydon,
Inc., New York, N. Y., a corporation of New York

Application October 9, 1956, Serial No. 43,281

Term of patent 3½ years

(Cl. D58—4)

The single figure is a perspective view of a plastic basket showing my new design.

I claim:

The ornamental design for a plastic basket, substantially as shown.
